UNITED STATES PATENT OFFICE.

LOUIS P. DESTIBATS, OF TRENTON, NEW JERSEY.

METHOD OF IMPREGNATING AND COATING MATERIALS.

1,135,777.

Specification of Letters Patent. Patented Apr. 13, 1915.

Application filed July 26, 1910. Serial No. 573,831.

To all whom it may concern:

Be it known that I, LOUIS P. DESTIBATS, a citizen of France, and resident of Trenton, in the county of Mercer and State of New Jersey, have invented a new and useful Improvement in the Method of Impregnating and Coating Materials, of which the following is a specification.

In impregnating and coating materials, such as fabrics, cords, cables and the like in the ordinary manner, where the air is not exhausted from the material, certain particles of air will remain in the material thus causing bubbles to form therein during the impregnating and coating process, which bubbles, as they burst, expose non-impregnated or coated portions of the material to external atmosphere and thus materially impair the quality and usefulness of the material for the purposes intended.

The object of this invention is to provide a new method for obviating the above faults, which method consists in first exhausting the air from the material and then passing the material through a liquid bath before exposing the material to external atmosphere, the said material being preferably thoroughly dried while the air is exhausted therefrom.

In the accompanying drawings, I have shown an apparatus for carrying out my improved method, said apparatus being particularly intended for use in carrying out the method for use in connection with fabrics.

Figure 1 represents an apparatus adapted for treating a fabric, in top plan, Fig. 2 is a longitudinal vertical central section through the same, Fig. 3 is an end view, a portion of the door for the vacuum chamber being broken away to more clearly show the parts within the chamber, and Fig. 4 is a transverse section taken in the plane of the line A—A of Fig. 2.

The roll of fabric to be treated is denoted by 1 and its core 2 is provided with suitable trunnions 3 resting upon supports 4 uprising from a wheeled truck 5, the wheels of which are fitted to travel along track sections 6. One of these track sections 6 is located permanently within a vessel 7, which vessel is herein shown as cylindrical in form and disposed horizontally. This vessel 7, when in use, is closed at both ends. In the present instance, the end 8 is shown permanently closed and the other end shown

as provided with a door 9 hinged at 10 to the body portion of the vessel 7. This door may be provided with a packing 11 for sealing the door air-tight when closed, bolts 12 or other suitable fastening devices serving to lock the door in its closed position. The truck bearing the roll of fabric may be moved into and out of the vessel 7 when the door 9 is opened by inserting a removable track section 6*, indicated in dotted lines, between the track sections 6 within and without the vessel 7. This track section 6* is removable to permit the opening and closing of the door 9. The interior of the vessel 7 may have the air exhausted therefrom in any suitable manner, as, for instance, by an air exhausting pump 13 of well known and approved form. An annular series of steam pipes 14 is properly supported within the vessel 7 around the roll of fabric 1, which steam pipes may be provided with the usual steam inlet and outlet pipes 15, 16, extending through the end wall 8 of the vessel. A liquid container 17 is mounted upon the top of the vessel 7, which liquid container is provided with a slot 18 in its bottom, through which slot the fabric is led from within the vessel 7 into the liquid container 17 for engagement with the liquid therein before the fabric comes in contact with external atmosphere.

Suitable flaps 19 may be provided in the bottom of the container 17 for engaging the opposite sides of the fabric as it leaves the slot 18 for preventing the liquid within the container 17 from being drawn into the interior of the vessel 7. The fabric web, as it leaves the liquid container 17, may be wound into a roll on a suitable core 20 having trunnions 21 supported by brackets 22 on uprights 23. A suitable heater 24 is located between the liquid container 17 and the winding roll for the purpose of drying the liquid impregnated and coated fabric. The fabric as it leaves the liquid container 17 may also pass through a pair of rolls 25 arranged to lead the fabric web from a roll 26 located within the vessel 7 straight through the slot 18 in the bottom of the liquid container 17. To thoroughly dry the fabric within the vessel 7, the fabric, as it leaves the roll, is passed around the longitudinally extended branches of the steam pipe within the vessel before being led around the roll 26 and upwardly through the liquid in the container 17.

- It will be seen from the above description that by inserting the roll of fabric to be treated into the vessel 7 and then exhausting the air from the said receptacle, that the air is also exhausted from the fabric. At the same time, the fabric is also thoroughly dried by the steam pipes hereinabove described or by any other suitable drying apparatus. The fabric is then led through the liquid in the container 17 thus permitting the liquid to thoroughly impregnate the fabric as well as coat the opposite sides thereof before the fabric comes into contact with external atmosphere.
- 10 While I have described this method in connection with an apparatus for treating fabric, it is to be understood that the same method may be readily employed for treating other materials, such as cords, cables, 15 and the like, without departing from the spirit and scope of my invention.
- It will also be observed that by the use of the method herein described, a complete 20 impregnation and coating of the material is provided and the formation of air bubbles in the fabric is absolutely prevented.
- 25 It is further to be understood that when

I speak of exhausting the air I do not necessarily mean that a vacuum as near perfect as possible must be created. The essential 30 method may be carried out with a so-called partial vacuum being created in the vessel.

What I claim is:—

The method of impregnating and coating fabrics consisting in first, confining a roll 35 of the fabric in a vessel; second, heating the vessel and exhausting the air therefrom; third, unwinding the fabric from the roll and passing it, in the form of a single layer, about in the vessel so that the vacuum will 40 affect all sides of the fabric; and fourth, passing the fabric in the form of a single layer out of said vessel and through another vessel containing a liquid bath before exposing the material to external atmosphere. 45

In testimony, that I claim the foregoing as my invention I have signed my name in presence of two witnesses, this twenty-third day of June 1910.

LOUIS P. DESTRIBATS.
